UNITED STATES PATENT OFFICE.

CHARLES GUTEERLET, OF PHILADELPHIA, PENNSYLVANIA, ASSIGNOR OF ONE-HALF
TO GEORGE D. COX.

DEINKING-MACHINE FOR PLATE-WIPERS.

1,191,506.

Specification of Letters Patent.

Patented July 18, 1916.

Application filed July 15, 1915. Serial No. 40,132.

To all whom it may concern:

Be it known that I, CHARLES GUTBERLET, a citizen of the United States, residing at Philadelphia, in the county of Philadelphia and State of Pennsylvania, have invented certain new and useful Improvements in Deinking - Machines for Plate - Wipers, of which the following is a specification.

The improved machine herein described is intended to remove and save the ink wiped off from the plate of die, plate and other engraving presses, by the wiping roll. It also cleanses the paper and permits it to be used several times.

In this machine are assembled mechanisms for cleansing the paper and collecting the ink, for permeating the paper with oil after the primary scraping off of the greater mass of the ink, an oil remover to remove this oil with the ink contained in it, devices for collecting this mixture and a tensional wiper collector for moving the wiper. With these main mechanisms are used a number of auxiliary devices which will be described in the detailed description of the best form of the machine of which I am at present aware. The machine can be used with presses in which the movement of the wiping roll is continuous or interrupted.

Figure 1 is a front elevation of my machine. Fig. 2 is a side elevation on the line $x-x$ of Fig. 1. Fig. 3 is a plan view on the line $y-y$ of Fig. 1, cut off at the line $x-x$. Fig. 4 is a section on the line $Z-Z$ of Figs. 1 and 3. Fig. 5 is a sectional view of the tensional wiper collector with its paper roll carrier, the casing of the tension mechanism being shown in section on line $u-u$ of Fig. 2. Fig. 6 is a section on same line, of the tensional wiper collector through all its parts, on a double scale. Fig. 7 is a detail of a pawl and ratchet mechanism for the tension partly in section on line $v-v$ on Figs. 1 and 3, and Fig. 8 is a further detail of same. Fig. 9 is a detail showing an automatic feed for the oil. Figs. 10 and 11 show a front and side view of scraping knives. Fig. 12 a holder for a knife adjustable in two directions. Fig. 13 is a side elevation of one arm of adjustable scraper holder.

The two back standards 2, 2, of a press, are shown, which serve to support the paper roll carrier 12 that carries the unused paper and its brake device. The driving shaft 13

with its drive wheel 14 can also support the frame of the improved machine herein described. This frame is very conveniently a pair of arms, 20, 20, extending back from the standards to which they are secured, and provided with arms 21, and having braces 22, and supporting the scraping and oiling mechanisms, and the tension device. At a convenient point where the paper, after it has been used to wipe the plate, is led into the machine, from the press, is placed the scraper 26. The paper (being kept taut by the tensional wiper collector as will be hereinafter described) is guided against the edge of the scraper, by the rollers, 129 and 36 or other suitable means. In the drawings the strip of paper passing out of the press is marked 24, and is shown as making an obtuse angle at its line of contact with scraper 26. That is, the planes formed by the faces of the paper on either side of the line formed by the edge of the scraper 26, make with each other, at this line of intersection, an obtuse angle. Adjustable mountings for the scraper 26 are shown in double scale in Fig. 12 where the plate 29 is adjustable lengthwise on arm 21 and two abutments 28, 28, form a holder in which a scraper can be adjusted and held so as to fit correctly against the paper. Beneath the scraper is a collector 23 for the ink scraped off the paper.

A roller 30, constitutes an oil permeator for the paper forming the wiper. It dips into an oil container 31 and is placed in the path of and in contact with the paper 24 passing out of the press after it has passed the scraper. This roller 30 is preferably made to revolve in the opposite direction to the paper's movement and a convenient means of turning it is the sprocket wheel 37 and the drive chain 65. This oil container 31 can be fed from a tank 32 by means of an automatic feeding device 33 consisting (see Fig. 9) of a valve 34 moved in the cock 35 by means of the float 75. The roller 36 serves to guide the paper 24 against the roller 30. The clutch 38 and its handle 39 serves to throw the roller 30 in and out of gear with sprocket wheel 37.

A part, at least, of the path of the paper wiper from the scraper 26, is preferably upward, because this will allow the oil to flow down the paper from the oil permeator, progressively to permeate it. This permeation is most complete as the paper passes over

the roller 30. The tensional wiper collector causes the paper to press against scrapers placed in the portion of the path of the wiper after the roller 30 has permeated the paper with oil so as to bring to the surface of the paper the mixture of oil and ink. The scrapers are preferably formed of a foundation of metal 48, with leather side pieces 49, 49, as shown in Figs. 10 and 11. The metal gives the stiffness required, and the leather side pieces alone coming into contact with the soaked paper, are less likely to cut it, but are equally efficient to bring to the surface and remove the mixture of oil and ink.

I consider the best form of oil remover to remove the oil that has filled the paper by the action of the oil permeator with the ink soaked out by the oil to be scrapers. The scrapers 41 and 42 work on the opposite sides of the paper. They can be suitably secured by clamps, 45, 45, in which the scrapers can be adjusted to desired positions. I prefer to add another scraper 43, that fits loosely in its carrier 44, and presses on the paper by its own weight only. These scrapers are best carried by an auxiliary frame 40, pivoted at one end to its support, thus allowing the paper's path to adjust itself to the increasing size of the roll of used paper. Beneath these scrapers is placed an oil collector 46 for the oil removed by the scrapers 41, 42 and 43, and a conveyor 47.

The tensional wiper collector winds the roll of used paper 50 and keeps taut the paper in its path through the machine while at the same time it puts only a light and yielding strain upon the paper forming the wiper, such as will not break it or tear it softened as it is and rendered easily torn by being permeated with oil. The shaft 51 on which the paper roll is carried, is urged continuously forward by a frictional contact between a pulley 52 carried by it and a constantly driven friction pulley 63. The details I use in practice are these. I drive a sprocket wheel 64 by a chain drive 65, this being connected by the hollow shaft 66 with the friction pulley 63. A face of pulley 63 is supported from the casing 60 by the ball bearings 61. The other side of pulley 63 is pressed against the pulley 52, preferably a washer of leather or other suitable frictional material being interposed between them. The pulley 52 is pressed toward pulley 63 by the head 54, carried by the screw 55 working in the casing 67. The ball bearing 53 is interposed between the head 54 and the pulley 52. To prevent the lessening of the tension I use the ratchet wheel 56 and pawl 57. This pawl has an arm 58 that rubs against the wheel 56. 59 is a leather washer placed on the arm and 69 a leather washer secured to the wheel (preferably sunk therein) which can, either or both, be used to increase

the friction between the arm 58 and wheel 56. The arm 58 may be sprung against the wheel 56 and for this purpose I can use the spring 68, the pinion 71 on which the pinion turns being provided with a head 72 and screwing into the casing 60.

The tension of the paper can be further assured by the strap 15 with the weight 16. The strap rests against the side of the roll 17 and the friction between it and the roll 75 caused by the weight 16 prevents the roll of unused paper 17 from unrolling more rapidly than it is pulled into the press.

The operation of the machine is as follows:—The wiping paper, when it comes out of the press, carries a layer of ink which is scraped off by the scraper 26. The strip of paper is under tension, and consequently, the rollers 36 and 129 bring its face firmly against the knife. After it passes this knife 26 the paper passes over the roller 30 which, rotating in the opposite direction to the motion of the paper, feeds the oil to it, thereby thinning and bringing to its surface the residue of the ink in the paper, so that the mixing of oil and ink can be removed readily by the scrapers 41, 43, 42, past which the paper moves after it has received the oil from the roller. The ink and the mixture of oil and ink are collected in suitable receptacles. The ink is usually in a condition for immediate use. The mixture of oil and ink is allowed to settle and the clear oil is recovered for another use, and, if desired, the heavier mixture of ink and oil can be separated.

The tensional wiper collector enables the improved machine to adapt itself to a press with an irregular feed of the wiping paper (as practically all embossing and plate printing presses are), provided the speed of the positively driven part is sufficient for this purpose and the tension being light enough not to tear the paper that has passed through the oil permeating device, variation of the adjustable tension being usually sufficient to enable the improved machine to operate with presses with many different movements of the wiping paper, so that the machine can be standardized. However, a change in rate of the positively driven part of the tension device can readily be effected, for instance, by change in the size of the sprocket wheel 64, if desirable, without any other change in the device.

The paper can sometimes be used again immediately, but for fear a slight residue of the oil remain in it, it is usually set aside for a few days to dry. Of course, while paper is the accepted material for wiping plates, the machine is applicable to any similar material. The paper can be used many times and the loss in ink and oil is very small, rendering the improved machine a very profitable one to operate.

I claim—

1. In a plate wiper deinking machine, the combination with the porous plate wiper, of an ink scraper placed in the path of the wiper, an oil permeator filling the wiper with oil placed in the path of the wiper beyond the ink scraper, an oil remover placed in the path of the wiper beyond the permeator, and a tensional wiper collector, the 10 tension of which is strong enough to cause it to draw the wiper but light enough not to tear the wiper when weakened by being filled with oil by the permeator.

2. In a plate wiper deinking machine, the 15 combination with the porous plate wiper, of an ink scraper placed in the path of the wiper, an oil permeator filling the wiper with oil, placed at a point in the path of the wiper beyond and elevated above the ink scraper, whereby the oil will flow downward on the wiper toward the ink scraper, an oil remover placed in the path of the wiper beyond the permeator and a tensionally operated wiper collector, the tension of 20 which is strong enough to cause it to draw the wiper but light enough not to tear the wiper while weakened by being filled with oil by the permeator.

3. The combination in a plate wiper deinking machine, with the porous plate wiper, in the form of a feeding roll, a collecting roll and an intermediate portion, of a freely revoluble shaft carrying the feeding roll of the plate wiper, an ink scraper placed in 25 the path of the wiper, an oil permeator filling the paper with oil placed in the path of the wiper beyond the ink scraper, an oil remover placed in the path of the wiper beyond the permeator, a tensional wiper 30 collector, the tension of which is strong enough to cause it to draw the wiper but light enough not to tear the wiper when weakened by being filled with oil by the permeator, and a brake acting to retard the 35 unrolling of the wiper upon the revoluble shaft.

4. In a plate wiper deinking machine the combination with a porous plate wiper, of an ink scraper placed in the path of the wiper, an oil permeator filling the wiper with oil placed in the path of the wiper beyond the ink scraper and elevated above same, positively operated mechanism for operating the oil permeator, an oil remover 40 placed in the path of the wiper beyond the oil permeator and a tensional wiper collector, the tension of which is sufficient to cause it to draw the wiper and yet light enough not to tear the wiper while filled 45 with oil by the permeator.

5. In a plate wiper deinking machine the porous plate wiper, the ink scraper, the oil

permeator, the oil remover, a swiveling carriage for the oil remover pivoted to the frame of the deinking machine and a tensional wiper collector, the tension of which is sufficient to cause it to draw the wiper yet light enough not to tear the wiper when the latter is filled with oil by the permeator. 65

6. The combination in a scraper for plate 70 wiper deinking machine of a central body of stiffer material of exterior layers of a fibrous material.

7. In a plate wiper deinking machine the 75 porous wiper in combination with the ink scraper, the oil permeator, oil remover consisting of scrapers, placed in the path of the wiper after it has passed the oil permeator, these scrapers being set to deflect the path of the wiper at their lines of contact with it, and a tensional wiper collector, the tension of which is sufficient to cause it to draw the wiper, yet light enough not to tear the wiper when the latter is filled with oil by the permeator. 80

8. The combination in a plate wiper deinking machine, of a porous wiper, an oil permeator for the wiper, a tensional wiper collector, and scrapers placed on both sides of the wiper on its path between the permeator and the collector. 85

9. In a plate wiper deinking machine, having a porous plate wiper, the combination with the oil permeator, of a tensional wiper collector and a series of scrapers impinging on opposite sides of the wiper, the path of the wiper being deflected at each 90 scraper. 95

10. The combination in a scraper for plate wiper deinking machines, with a central 100 body of spring metal of exterior layers of leather.

11. In a plate wiper deinking machine the combination with a porous plate wiper, the ink scraper, the oil permeator consisting of a roller placed in the path of the wiper beyond the ink scraper and elevated above the ink scraper and having a portion of its surface in contact with the wiper, mechanism driving the roller in a direction to cause the 105 surface of the roller in contact with the wiper, to move in the opposite direction to the wiper's movement, the oil remover and a tensional wiper collector, the tension of which is sufficient to cause it to move the 110 wiper yet light enough not to tear the wiper when the latter is filled with oil by the permeator. 115

In testimony whereof I affix my signature in presence of two witnesses.

CHARLES GUTBERLET.
